SHOE MACHINE

Bernard S. Steiner, Kirksville, Mo., assignor to
 The Peerless Machinery Company, Boston,
 Mass., a corporation of Massachusetts

Application December 8, 1934, Serial No. 756,641

10 Claims. (Cl. 12—51)

This invention pertains to shoe machinery and relates more particularly to mechanism for compressing and shaping the marginal portion of the quarter of a shoe upper. The upper edge of a finely finished shoe should be free from any appearance of undue bulk, thickness, or clumsiness of construction, and the margin of the upper should fit snugly about the ankle of the wearer (or about the top of the last during manufacture). While these characteristics are desirable, they are not always easy to attain, especially in making the cheaper grades of shoe, where expensive operations must be avoided and where the work must be done at a rate of speed which discourages or precludes any great care on the part of the operator.

The upper of a shoe usually comprises several thicknesses of material, for example, an outer member and a lining, and frequently reinforce or doubler members interposed between such outer member and lining. Customarily the outer member is folded inwardly at its margin, and the corresponding margin of the lining is brought into contact with the inwardly folded material of the outer member, and the parts are united by a sewed seam, the stitches passing through both thicknesses of the folded material and through the lining. In order to avoid bulkiness it has heretofore been proposed to skive the margin of the lining to a very thin feather edge before securing it to the outer member of the upper, but the skiving operation adds materially to the expense of making the shoe, and the skived lining has a tendency to tear out after a comparatively short period of use.

As the result of considerable experiment, I have found that the appearance of the margin of the upper may be considerably improved by compressing and compacting the margin of the lining, for example, by passing it between pressure rolls, so as substantially to reduce the thickness of the marginal portion of the lining material. By proceeding in this manner the raw edge of the lining is compacted and made thinner, but is not substantially weakened and does not show any tendency to tear out when in use.

In stitching the lining to the outer member of the upper, the folded material of the outer member is guided by means of a gauge, but frequently by reason of haste or carelessness on the part of the operator, or on account of the character of the materials employed, the contact of the work with the gauge causes the fold to assume a distinct bead-like or thickened form with a tendency to curl outwardly and thus leave a distinct and

unsightly gap between it and the lining, which is thus exposed to view. The lining is under-trimmed, usually concomitantly with the stitching operation, but this under-trimming leaves the lining with a raw edge which is sometimes spread during the trimming operation so that it may at least have the appearance of being thicker after trimming than is the body of the lining material.

The above-noted defects are not such as can be cured in the lasting operation or in the usual subsequent operations, and not only detract from the nicety of appearance of the finished shoe, but prevent the edge of the upper from fitting as snugly about the foot of the wearer as is desirable for looks and comfort.

In the course of my experiments above noted (with the object of thinning the edge of the lining by compacting or pressing such edge) I have discovered that the folded marginal portion of the outer member may readily be compressed and thinned concomitantly with the thinning of the lining, as for example by the employment of presser devices of appropriate shape, for instance rollers having complementally shaped beveled edges. By such means the entire margin of the shoe upper may be compacted and thinned, and at the same time caused to assume a slight inward curvature so that the top of the shoe tends snugly to fit about the last. The pressure, employed for thinning the margin of the upper, flattens and elongates the folded edge of the outer member so that the lining appears to have been under-trimmed further than is ordinarily possible in the trimming machine, thus further enhancing the appearance of the completed shoe.

The principal object of the present invention is to provide means for shaping the marginal portion of the shoe upper, as above described, by the proper application of pressure, and preferably heat, so as to flatten the fold or bead in the outer material of the upper; compress the edge portion of the lining material; compact the margin of the upper so that its component parts do not show any tendency to gap, and to reduce the apparent thickness of the upper; and preferably to cause the margin of the upper to assume a slight curvature (in vertical section) with its concavity inward so that in the completed shoe the edge of the upper tends snugly to hug the foot of the wearer.

Further objects of the present invention are to provide improved drive connections for a bodily movable presser roll such as to ensure a positive drive of said roll in all positions of the latter without substantial interference with the

desired bodily movement of the roll and without resort to the use of a spring or similar type of flexible shaft such as commonly employed in these machines. A further object is to provide drive connections for the bodily movable roll such that a given roll may be exchanged for another if desired without dismantling the machine or requiring special tools or special skill or the expenditure of an undue amount of time. A further object is to provide improved means for supporting the bodily movable roll so as to facilitate the application of the spring pressure for urging it toward the other roll and also to facilitate its movement away from the other roll at will by means of a pedal or other manually actuatable device. A further object is to provide presser devices, for example rolls having complementary beveled faces, as to perform the above operations in a simple and expeditious manner.

Other objects and advantages of the invention will be apparent from perusal of the following more detailed description in which reference is made to the accompanying drawing, wherein

Fig. 1 is an elevation of the machine, viewed from the left side, with certain parts broken away;

Fig. 2 is a fragmentary elevation of the machine, viewed from the right side, with certain parts in vertical section;

Fig. 3 is a front elevation of the machine with certain parts omitted;

Fig. 4 is a section to larger scale on the line 4—4 of Fig. 2;

Fig. 5 is a fragmentary elevation illustrating one element of the drive mechanism for the upper presser roll;

Fig. 6 is a fragmentary elevation illustrating another element of such drive mechanism;

Fig. 7 is a fragmentary vertical section through the presser rolls, showing the top edge portion of a shoe upper;

Fig. 8 is a fragmentary, diagrammatic vertical section, showing the upper marginal portion of a shoe upper, to large scale, as it may appear at the completion of the stitching operation;

Fig. 9 is a similar view, showing the appearance of the margin after it has been shaped by the mechanism herein disclosed; and

Fig. 10 is a diagrammatic view illustrating presser rolls of different peripheral contour.

In Fig. 8, I have shown, to large scale and with some exaggeration for purposes of description, the appearance of an ordinary shoe upper after the lining has been secured to the outer member 55 of the upper. While in ordinary practice either or both the outer member and the lining may be provided with reinforce material, such as a doubler, such reinforce material has been omitted in Fig. 8 for simplicity of illustration. The outer member U of the upper is folded at F so that its free edge lies at E. A seam comprising stitches S unites the lining L to both thicknesses of the fold F. The edge e of the lining is under-trimmed, usually concomitantly with the stitching, so that 65 it lies slightly below the top of the fold F which is intended to conceal the edge e. While reasonably desirable results may be obtained by skillful operators using good materials, it frequently happens that the fold F assumes a beaded form, as 70 shown in Fig. 8, the material of the fold leaning outwardly and away from the edge e of the lining, thus leaving a gap G between the parts and exposing the raw edge e of the lining, which is sometimes left rough or apparently thickened by 75 the under-trimming operation. By the use of

the apparatus now about to be described, the margin of the upper may be so pressed and shaped as to assume the finished appearance illustrated in Fig. 9, wherein the fold F' has been flattened, the edge e' of the lining thinned down, and the 5 entire marginal portion of the upper compacted and preferably caused to assume a slight curvature with its concavity at the inner side as indicated at X. The margin of the upper thus has a far neater and more finished appearance and is 10 adapted to fit more perfectly about the foot of the wearer than when my novel shaping operation is not performed.

Referring to the drawing, the numeral 1 designates the base of the machine frame, such 15 base being adapted to be mounted upon any appropriate support, for example a bench or table, and to be bolted or otherwise secured to the latter. From this base rises a column 2 which carries vertically spaced, laterally extending arms 3 20 and 4.

A shaft 5 is arranged to turn in a bearing in the column 2 and in an aligned bearing in a bracket 6, forming a part of the arm 3. The shaft 5 extends rearwardly beyond the column 2 and 25 has fixed on its projecting end a drive pulley 7 and a sprocket wheel 8. At its opposite end the shaft is furnished with a pinion 9 (Fig. 1) which meshes with a gear 10 on a shaft 11 journaled in suitable bearings in the bracket 6 and a second 30 bracket 12 also carried by the arm 3. At its forward end the shaft 11 has fixed thereto by a set screw 11^a the lower presser roll 13, which as here illustrated is provided with a peripheral edge comprising a cylindrical portion and a beveled 35 portion.

A sprocket chain 15 engages the sprocket wheel 8 and passes around a sprocket 16 on a shaft 18 mounted to turn in a long bearing opening in the column 2. At its forward end (Fig. 2) this 40 shaft 18 is provided with a substantial spherical head 19 united to the shaft proper by a neck portion 21^a (Fig. 5) of reduced diameter. This head 19 telescopes within an axial bore in an elongate rigid, tubular transmission member 20. The head 45 19 is furnished with a slot 21 (elongate axially of the shaft 18 and closed at both ends), and this slot receives a pin 21^b whose opposite ends are fixed in the walls of the tubular transmission member 20. The opposite end of this member 20 50 telescopes over a spherically curved head portion 22 of a shaft 23 mounted to turn in bearings in a movable bracket 24. At its forward end the shaft 23 has fixedly secured thereto the upper presser roll 25.

The head 22, at the rear end of the shaft 23, is connected to the latter by a neck portion 22^a of reduced diameter, and the head member 22 is furnished with an elongate slot 22^b, which is open at its rear end and which receives a pin 22^c whose opposite ends are fixed in the walls of the tubular rigid transmission member 20. The shaft 23 is furnished with a depression 23^a which normally receives the inner end of a set screw 23^b in a collar 23^c which prevents axial movement of this 65 shaft. However, by retracting the set screw from the depression 23^a, the shaft 23 may readily be moved axially from out of its bearing, the open ended slot 22^b permitting ready separation of the shaft from its driving pin 22^c. It is thus readily 70 possible to remove the shaft 23 with the upper presser roll 25 for repairs, or for substitution of a new presser roll for one which has become worn, or for one of a different peripheral contour. As here shown the upper presser roll 25 has a con- 75

5 convex peripheral edge 26 complementary of the peripheral edge of the lower roll 13. Obviously, rolls may be provided for imparting any desired shape to the margin of the upper, for example rolls 5 having complementary concave and convex faces respectively, beveled faces alone or with surfaces of other shape, as indicated for instance in Fig. 10.

10 The bracket 24, which provides the bearing for the upper presser roll shaft, is pivotally mounted 10 on a shaft 27 arranged in an elongate bearing in a bracket member 28 carried by the arm 4. A spring 29 interposed between the brackets 24 and 28 permits a slight yielding of the bracket 24 axially of the shaft 23. The bracket 24 is furnished 15 with a socket, open at its top, for the reception of a heating unit 30, which may be an electrical unit supplied with current through a flexible conductor 31. This unit keeps the bracket 24 at a predetermined temperature, the heat from the bracket 20 being transmitted to the presser roll 25, which contacts with the bracket, so that the upper presser roll may be kept hot to facilitate the pressing operation.

25 A shaft 32, substantially parallel to the shaft 18 and to the left of the latter, is mounted to turn in aligned bearings in the column 2 and in the bracket 28, and adjacent to its forward end this shaft is furnished with a crank arm 32a carrying a crank pin or lifter 33 which rests 30 against the right-hand face of the pivoted bracket 24 at a point in a plane substantially above the pivotal axis of said bracket.

35 At a point spaced forwardly from the column 2 the shaft 32 is provided with a collar 34 (Fig. 1), which may be held fixed to the shaft by means of an elongate set screw 35. The collar also carries an arm 36 preferably provided with an opening at its outer end to receive the end of a flexible or other connecting element 37 leading downward 40 to a treadle. The set screw 35 is preferably of such length that it may contact with the upper arm 4 of the frame at times, and thus limit turning of the shaft 32 in a clockwise direction, as viewed in Fig. 3.

45 The upper arm 4 of the frame is furnished with a bracket 38 projecting to the left, and this bracket has a screw threaded opening for the reception of an adjusting screw 39, whose end bears against a compression spring 40, which exerts a 50 resilient thrust against the upper part of the pivoted bracket 24,—tending to turn said bracket in a clockwise direction about the axis of the shaft 27.

55 From inspection of Fig. 3 it may be noted that the shaft 27 is located slightly to the left of a vertical plane passing through the axis of the shaft 11, and in a horizontal plane above that of the bite of the presser rolls, while the pin 33 is located well above the shaft 27, and preferably at a point substantially vertically above the shaft 23. 60 With this arrangement a slight downward motion of the arm 36 rocks the shaft 32, and by engagement of the pin 33 with the upper part of the bracket 24, causes the bracket 24 to turn about its pivot shaft 27, thereby bodily lifting the upper 65 presser roll 25 away from the lower presser roll 13. However, as soon as the arm 36 is released, the spring 40 urges the bracket 24 and the presser roll 25 toward normal position, such movement being limited by engagement of the set screw 35 with the frame. By reason of the difference in 70 the lengths of the lever arms through which the spring 40 and the resisting force of the work act, a very heavy pressure is obtained. By loosening the set screw 35, the collar 34 with its arm 36 75 may be adjusted circumferentially of the shaft

32, so that the stopping of the clockwise movement of the bracket about the shaft 27 by the spring 40 may be predetermined, thus fixing the normal spacing between the peripheries of the presser rolls. 5

10 Preferably a work supporting table T is mounted on the lower arm 3 of the frame to assist the operator in holding the work in proper position while presenting its edge for engagement by the presser rolls. 10

15 In operation, assuming that the bracket 24 has been heated so as to heat the upper presser roll 25, the operator, having the work in readiness with its edge folded, and with the seam completed, places his foot on the treadle (not shown), thereby depressing the arm 36 and raising the upper presser roll 25 so as to permit the insertion of the edge of the upper between the rolls. The pulley 7 is turned at proper speed by means of a belt (not shown), and thus drives the shafts 20 5 and 18, thereby turning the presser rolls in opposite directions. After introducing the work between the rolls, the operator immediately releases the treadle, whereupon the spring 40 forces the rolls toward each other. Such lifting of the 25 presser roll 25 does not interfere with the driving of this roll, since the described connections between the shafts 18 and 23, including the spherical heads and reduced neck portions of said shafts, are such as to allow the rigid transmission member 20 to take up an angular position 30 relatively to the axes of the shafts 18 and 23, and thus permit shaft 23 to be moved out of axial alignment with the shaft 18, while at the same time being driven by the latter. 35

40 As the rolls 25 and 13 rotate in contact with the work, they press the edge of the latter, shaping it in conformity with the peripheral configurations of the rolls, and so compressing the material as to provide a properly finished 45 edge. By reason of the heating of the upper roll, the work receives a permanent set while being compressed, so that it retains its shape after it has passed between the rolls.

50 As above noted, the upper presser roll with its 55 shaft 23, as well as the lower roll 13, may readily be removed for replacement or repairs without dismantling the machine, while the employment of the rigid transmission member 20, which receives at its opposite ends the spherically curved 55 head portions 19 and 22 of the shafts 18 and 23 respectively, permits the roll 25 to be driven without interruption regardless of the thickness of the work interposed between the rolls, and without resort to flexible shifting or similar devices which are not durable and which ordinarily cause much trouble to the user.

55 If desired, an additional and adjustable stop 60 41, carried by a bracket secured to the part 25, may be arranged to contact with the table T or other convenient part, thereby to relieve the pin 33 from pressure except when such pin is actuated to separate the rolls.

65 While I have herein illustrated one desirable embodiment of the invention by way of example, I wish it to be understood that the invention is not necessarily limited to the specific details herein disclosed, but that equivalent arrangements are regarded as falling within the scope of the invention. 70

I claim:

75 1. A machine for compressing and shaping the upper edge of the quarter of a shoe whereby to compact the marginal portion of an under-trimmed lining and to flatten the folded marginal 75

- portion of the outer member of the quarter while imparting a slight inward curvature to the top edge of the quarter, said machine comprising a pair of presser rolls between which said top edge of the quarter may be passed, said rolls having peripheral edges comprising surfaces which are inclined relatively to the axes of the respective rolls, the inclined surface of one roll sloping outwardly and away from the roll axis and being 5 designed to contact the outer surface of the top of the quarter, and the inclined surface of the other roll sloping inwardly toward the roll axis and being designed to engage the lining of the quarter, drive means operative positively to turn 10 the rolls in opposite directions, means supporting one roll for bodily movement toward and from the other, and resilient means designed and arranged to urge the bodily movable roll toward the other with powerful pressure.
20. 2. A machine for compressing and shaping the upper edge of the quarter of a shoe whereby to compact the marginal portion of an under-trimmed lining and to flatten the folded marginal portion of the outer member of the quarter while 25 imparting a slight inward curvature to the top edge of the quarter, said machine comprising a pair of presser rolls between which said top edge of the quarter may be passed, said rolls having peripheral edges comprising substantially cylindrical portions and adjacent beveled portions, the beveled edge portion of one roll flaring outwardly away from the roll axis and being designed to contact the outer surface of the top of the quarter and the beveled edge portion of the other 30 roll sloping inwardly toward the roll axis and being designed to engage the lining of the quarter, drive means operative to turn the rolls in opposite directions, means supporting one roll for bodily movement toward and from the other, 35 and resilient means designed and arranged to urge the bodily movable roll toward the other roll.
3. In a machine of the class described, a pair of complemental presser rolls, means providing 45 a fixed axis about which one roll turns, a movable bracket provided with a bearing opening parallel to said fixed axis, a shaft constituting a pivotal support for the bracket, the latter being also movable axially of said shaft, a shaft for 50 the other roll turning in said bearing opening in the bracket, means for moving said bracket about its pivotal support to separate the rolls, a spring urging the bracket endwise along its 55 pivotal supporting shaft, and drive means for said roll shaft normally operative to turn it in all positions of the bracket.
4. In a machine of the class described, a pair of complemental presser rolls, a shaft for one roll turning in fixed bearings, a movable bracket 60 provided with a bearing opening in which turns a second shaft parallel to said first shaft, means fixing the second roll to said latter shaft, said latter shaft having a depression and a releasable retaining element normally entering said depression to prevent axial movement of said shaft in its bearings, the latter shaft having an open ended slot in one end, and drive means for said latter shaft operative to turn the latter in all 65 positions of the movable bracket, said drive means comprising a pin normally disposed in said slot, said latter shaft with its roll being freely separable from the driving connections by axial movement of the shaft after retraction of the retaining element from said groove.
70. 5. In a machine of the class described having

a pair of complemental presser rolls and a movable bearing for one of said rolls so constructed and arranged as to permit bodily movement of the latter roll toward and from the first, in combination, means for driving the bodily movable roll in all positions of the latter, including a shaft to which said roll is fixed, said shaft having a spherically curved head at one end, the head having an axially elongate slot therein, a drive shaft turning in fixed bearings, said drive shaft 10 having a spherically curved head provided with an axially elongate slot, a rigid transmission member having hollow end portions which respectively receive the heads of said shafts, a pin fixed in each of said hollow end portions of the 15 transmission member, said pins extending into the slots in the respective shaft heads, and means for turning the drive shaft.

6. In a machine of the class described having a pair of complemental presser rolls and a movable bearing for one of said rolls so constructed and arranged as to permit bodily movement of the latter roll toward and from the first, in combination, means for driving the bodily movable roll in all positions of the latter, including a shaft 20 to which said roll is fixed, said shaft having a spherically curved head at one end, said head having an axially elongate slot open at the end of the shaft, a drive shaft also having a spherically curved head at one end, said head having an axially elongate slot closed at both ends, a rigid transmission member hollow at each end, each such hollow end telescoping over one of the spherical shaft heads respectively and pins 25 extending diametrically across said hollow ends 30 of the transmission member and through the slots in the respective shaft heads.

7. In a machine of the class described having a pair of complemental presser rolls and a movable bearing for one of said rolls so constructed 40 and arranged as to permit bodily movement of the latter roll toward and from the first, in combination, means for driving the bodily movable roll in all positions of the latter, including a shaft to which said roll is fixed, said shaft having an axially elongate slot in one end, a drive shaft turning in fixed bearings and having an axial slot in one end, a rigid transmission member 45 having hollow end portions which telescopically receive the slotted ends of said shafts, said ends being of such shape and dimensions as to permit the transmission member to swing angularly with respect to the axes of the shafts, and members fixed to the end portions of the transmission member and entering the slots in said shaft 50 ends, thereby to transmit rotation of the drive shaft through the transmission member to the 55 roll carrying shaft.

8. In a machine of the class described having a pair of complemental presser rolls, a shaft for 60 the lower roll arranged to turn in fixed bearings, a movable bracket having a bearing for the shaft carrying the upper roll, pivotal means for the bracket providing a pivotal axis offset laterally from the vertical plane through the axis of the 65 bottom roll, and in a plane above the horizontal plane of the bite of the rolls, a spring engaging the bracket at a point more remote from the bracket axis than is the bite of the rolls, said spring tending yieldingly to swing the bracket 70 so as to urge the upper roll toward the lower roll, a lifter member engaging the bracket at a point more remote from the bite of the rolls than is the point at which the spring engages the bracket and substantially vertically above the 75

axis of the lower roll, and means operative to move said lifter member toward the vertical plane through the axis of the bracket.

9. In a machine of the class described having a pair of complemental presser rolls, a shaft for the lower roll arranged to turn in fixed bearings, a movable bracket having a bearing for the shaft carrying the upper roll, pivotal means for the bracket providing a pivotal axis offset laterally from the vertical plane through the axis of the bottom roll, and in a plane above the horizontal plane of the bite of the rolls, means tending to swing the bracket about its pivotal axis so as to urge the upper roll toward the lower roll, a rock shaft having its axis substantially parallel to the pivotal axis of the bracket, an arm secured to said rock shaft and carrying a lifter member engageable with the bracket at a point above the pivotal axis of the latter, a collar on the shaft, an actuating arm carried by said collar, and a set screw normally fixing the collar in adjusted position on the shaft, said set screw having a projecting portion operative by contact with a fixed part of the machine frame to limit rotation of the rock shaft and thereby to limit turning of the bracket. 5
10. In a machine of the class described having a pair of complemental presser rolls, a shaft for the lower roll arranged to turn in fixed bearings, a movable bracket having a bearing for the shaft carrying the upper roll, pivotal means for the bracket providing a pivotal axis offset laterally 10 from the vertical plane through the axis of the bottom roll and in a plane above the horizontal plane of the bite of the rolls, an adjustable spring engaging the bracket at a point above the horizontal plane of the upper roll axis, said spring tending to swing the bracket about its pivot so as to urge the upper roll toward the lower roll, a shaft disposed above but substantially parallel to the pivotal axis of the bracket, a lifter member fixed to said shaft and engaging the bracket at 15 a point above the horizontal plane of the point of engagement of the spring with the bracket and an actuating arm fixed to said last-named shaft. 20

10. In a machine of the class described having

BERNARD S. STEINER.
